UNITED STATES PATENT OFFICE.

LOUIS V. ARONSON, OF NEWARK, NEW JERSEY.

DESIGN FOR A CENSER.

No. 38,986.

Specification for Design.

Patented Jan. 7, 1908.

Application filed August 20, 1907. Serial No. 389,416. Term of patent 7 years.

To all whom it may concern:

Be it known that I, LOUIS V. ARONSON, a citizen of the United States, residing in the city of Newark, county of Essex, and State of New Jersey, have invented a new, original, and ornamental Design for Censers, of which the following is a description.

Figure 1 is a top plan view, and Fig. 2 is a side elevation of a censer embodying and containing my design.

I claim
The ornamental design for censers as shown.

LOUIS V. ARONSON.
